UNITED STATES PATENT OFFICE.

HENRY E. PFEIFFER, OF MONROE, WISCONSIN, ASSIGNOR OF ONE-HALF TO FRED. W. PFEIFFER, OF MONROE, WISCONSIN.

MACHINE FOR SURFACING BUTCHER-BLOCKS.

No. 921,451.

Specification of Letters Patent.

Patented May 11, 1909.

Application filed August 14, 1908. Serial No. 448,593.

To all whom it may concern:

Be it known that I, HENRY E. PFEIFFER, a citizen of the United States, residing at Monroe, in the county of Green and State of Wisconsin, have invented a new and useful Machine for Surfacing Butcher-Blocks, of which the following is a specification.

This invention relates to planing devices and more especially to a device for dressing 10 the surface of butcher blocks and the like.

The object of the invention is to provide a device of the character described which may be operated by a person of ordinary mechanical skill, will be of improved construction, readily applied, automatic in operation, and easily kept in order.

The invention consists in general of a spindle adapted to be mounted on the center of a butcher block or the like, an adjustable 20 arm arranged to rotate about said spindle, and a tool supported on said arm and arranged to move along the arm as it is rotated about the spindle.

The invention further consists in certain 25 novel details of construction and combinations of parts hereinafter fully described, illustrated in the accompanying drawings, and specifically set forth in the claims.

In the accompanying drawings, like characters of reference indicate like parts in the several views, and:—Figure 1 is a side elevation of a device constructed in accordance with this invention. Fig. 2 is a top plan view of said invention, a part being broken 35 away to show more clearly the tool holder and the tool carrying bar. Fig. 3 is a section on the line "A—B" of Fig. 1. Fig. 4 is a section on the line "C—D" of Fig. 1. Fig. 5 is an end view of the revolving tool carrying 40 bar arranged to show the reducing gears used for the feed of the tool.

The numeral 10 indicates the main spindle of the device and is provided at its upper end with a square 11, for the purpose of receiving 45 a wrench or the like, and at its lower end with a wood screw 12, so that the spindle may be screwed firmly into the surface of the block to be dressed at a point substantially in the center thereof. Upon the spindle 10 is 50 mounted a bracket 13, so arranged that the spindle may rotate freely therein. This bracket 13 is provided with a pair of spaced arms as clearly shown in Fig. 1 and intermediate of the arms is a journal 14. A

sleeve 15 is held to rotate upon the spindle 55 10 and is provided at one side with a bearing 16 arranged to receive the end of a shaft 17 which passes through the bearings 14 and into the bearings 16. This shaft 17 is of sufficient length to extend outward well over 60 the edge of the block to which the device is to be applied and is supported at the outer end by means of telescopic standards 18, provided at their upper ends with bearings 19, and at their lower ends with feet 20, 65 adapted to be secured to the floor. Upon the outer end of the shaft 17 is provided a crank handle 21 rigidly attached to the shaft so as to rotate the same as the crank handle is turned. The sleeve 15 extends downward 70 along the spindle 10 and passes through the lower arm of the bracket 13.

Above the lower arm of the bracket 13 is secured a beveled gear 22 provided with a downwardly extending hub 23, which passes 75 through a limb 24 attached to a block 25. A gear 26 is keyed to the shaft 17 and meshes with the gear 22. Attached to the block 25 is a bar 27 arranged to be held in position relative to the block 25 by means of 80 bolts 28 passing through said block and into threaded holes 29, spaced along said bar. By this arrangement it is possible to adjust the relative positions of the block and bar so that a greater or lesser length of bar may be 85 caused to project to one side or the other of the spindle 10 as may be desired. It will now be plain that the rotation of the crank handle 21 will rotate the gear 22 and thus carry the bar 27 around the spindle 10. For 90 the purpose of taking the strain off of the spindle as the bar revolves therearound there is provided one or more rollers 30 located on the under side of the bar and so arranged as to bear against the surface of the 95 block and prevent the outer end of the bar from sagging downward.

The bar 27 is slotted longitudinally as indicated at 31 and in this slot is provided a feed screw 32 extending from one end of the 100 bar to the other. Mounted on the feed screw 32 and closely fitting the slot 31 is a tool holder 33 having the usual feed nut 34 rigidly connected thereto. A tool of suitable form as indicated at 35 is held in this 105 tool holder by means of a set screw 36. The outer end of the bar 27 is turned up as indicated at 37 and a train of gears 38 is pro-

vided thereon one of which is rigidly attached to the feed screw 32. A feed screw handle 39 is also attached to this feed screw so that the same may be rotated by hand if 5 desired.

Rigidly attached to the under side of the lower arm of the bracket 13 is a gear 40. Supported in a bracket 41 attached to the upper side of the bar 27 and in the upturned 10 end 37 of said bar is a telescopic shaft 42, on which is mounted one of the train of gears 38 at the outer end and which carries a gear 43 at the inner end meshing with the gear 40.

For the purpose of holding the parts in 15 adjusted relation there are provided collars 44 secured by means of set screws 45 at whatever points may be desired.

For the purpose of understanding the operation of the device the upper surface of a 20 butcher block has been indicated in Fig. 1 at 46, but little more than one half of said surface being shown.

When it is desired to dress the surface of a block such as 46, the arm 27 is so positioned 25 relative to the block 25 that the extreme end of the arm will slightly overlap the edge of said block and the tool holder 34 run out to just contact with said edge, when the device is in position. A substantially central point 30 is then located and the spindle 10 is screwed therein. The standards 20 are attached firmly to the floor and the telescoping portion adjusted so as to bring the shaft 17 to a level. The tool is now set to the proper 35 depth of cut desired and the handle 21 rotated. This rotates the gear 26 which in turn rotates the gear 22 and carries around the arm 27 through its attachment 25. At the same time that this takes place the gear 40 43 moves around the gear 40, the latter being held stationary by its attachment to the bracket 13, and this causes the rotation of the shaft 42. By means of the train of gears 38 the rotation of the shaft 42 in turn rotates 45 the shaft 32 and causes the tool holder 33 to move inward as the arm 27 revolves around the spindle. The path of the tool is thus made spiral and the entire surface of the block is gone over and dressed down to an 50 even and level surface. In case one cutting is not sufficient to accomplish this purpose, the tool holder may be run out to the end a second or third time by means of the handle 39, one of the gears 38 being unkeyed to permit 55 the accomplishment of this without it being necessary to rotate the arm 27, and the operation repeated after the tool has been reset. The surface of the block is thus brought into the proper condition, and it will be noted 60 that this is accomplished with less labor and skill than where it is attempted to surface

the block by means of the ordinary hand plane or scraper.

It is obvious that changes may be made in the form and construction of this device 65 without departing from the material principles thereof. It is not therefore desired to confine the invention to the exact form herein shown and described, but it is wished to include all such as properly come within 70 the scope thereof.

Having thus described the invention, what is claimed as new, is:—

1. In a device of the kind described, a spindle adapted for attachment to a butcher 75 block, a sleeve mounted for rotation around the spindle, a block attached to the sleeve, a gear rigid with the sleeve, a second gear meshing with the first mentioned gear, a bracket mounted on the spindle, a shaft supported in the bracket and carrying the second gear, standards supporting the outer end of the shaft, means for rotating the shaft to cause the block to move around the spindle, a third gear rigidly attached to the bracket, 80 a tool carrying arm adjustably attached to the block, a force gear meshing with the third gear, a telescopic shaft on the arm carrying the force gear, a feed screw supported on the arm, a train of gears connecting the telescopic shaft and feed screw, a tool holder supported on the feed screw, and a tool carried by the tool holder.

2. In a device of the kind described, a spindle adapted for attachment to a butcher 95 block, a sleeve mounted for rotation around said spindle, a block rigidly attached to said sleeve, a gear rigidly attached to said sleeve, a second gear meshing with the first mentioned gear, a bracket mounted on said spindle, a shaft supported in said bracket and carrying said second gear, standards supporting the outer end of said shaft, a crank handle arranged to rotate said shaft and cause the block to move around the spindle, 100 a third gear rigidly attached to said bracket, a tool-carrying arm adjustably attached to said block, a force gear meshing with the third gear, a telescopic shaft on said arm carrying said force gear, a feed screw supported 105 on said arm, a train of gears connecting said telescopic shaft and feed screw, a tool holder supported on said feed screw, and a tool carried in said tool-holder.

In testimony that I claim the foregoing as 115 my own, I have hereto affixed my signature in the presence of two witnesses.

HENRY E. PFEIFFER.
